United States Patent Office

Des. 177,668
Patented May 15, 1956

177,668

DESK AND SEAT COMBINATION

Robert M. Fosso, Seattle, Wash.

Application April 7, 1955, Serial No. 35,397

Term of patent 7 years

(Cl. D33—7)

Fig. 1

Fig. 2

Fig. 3

Fig. 1 is a perspective view of a desk and seat combination embodying my design.

Fig. 2 is a top plan view of the same.

Fig. 3 is an elevation of the closed side thereof.

I claim:

The ornamental design for a desk and seat combination, as shown.
